UNITED STATES PATENT OFFICE.

JESSE CHENOWETH, OF EAST SALT LAKE CITY, UTAH.

CROSS-CHAIN HOOK OPENER AND CLOSER.

Application filed June 10, 1926. Serial No. 115,043.

The invention relates to devices for facilitating the removal of worn or broken cross chains from tire chains, and the substitution of new cross chains, and it is the object of 5 the invention to provide a device of this character which is exceptionally simple and inexpensive, yet will be efficient, rapid, and very easy to operate.

With the foregoing in view, the invention 10 resides in the novel subject matter herein-after described and claimed, the description being supplemented by the accompanying drawing.

Fig. 1 is a perspective view of the complete device constructed for operation by 15 foot power.

Figs. 2 and 3 are enlarged perspective views showing the use of the device in opening a hook of a cross chain to permit removal thereof from a side chain.

Figs. 4 and 5 are perspective views showing the manner in which the device is used to close the hook of a cross chain after application thereof to a side chain.

The form of construction herein disclosed has in actual use proven to be very efficient, rapid and generally desirable, for which reasons, the details herein disclosed may be considered as preferred. However, while 25 these details will be hereinafter specifically described, it is to be understood that within the scope of the invention as claimed, variations may be made and moreover, it may be explained that while the device herein disclosed is constructed to be operated by the user's foot, provision could be made for actuating it by power.

The numeral 5 designates a standard having supporting legs, said standard being 40 preferably formed in part of two long metal bars 6 whose major portions are disposed in spaced parallel relation and an intermediate comparatively short bar 7 whose upper end is secured by rivets or the like 8 between 45 the intermediate portions of said bars 6. The lower ends of the bars 6 are curved forwardly and outwardly to provide a pair of supporting legs 9 and the bar 7 is rearwardly curved to provide an additional supporting leg, the lower extremities of all of these bars being preferably given a quarter twist, providing feet 10 to rest upon the ground or upon a floor.

A vertically elongated, comparatively 55 heavy bar 11, has its lower end secured between the upper ends of the bars 6, by

rivets or the like 12, to complete the standard structure, the upper front corner of this bar 11 being provided with a chisel-like nose 13 and with a sharpened edge 14 extending 60 rearwardly from this nose to the rear edge of the bar, these formations being provided for purposes to appear.

Slidably surrounding the bar 11, is a yoke 15 secured by rivets or the like 16 to a vertical shank 17 which slidably engages the rear edge of said bar 11. The upper end of this shank is provided with a forwardly extending arm 19 having a downturned front end 20 of chisel-like form to slidably engage the front edge of the formation 13, as shown for instance in Figs. 3, 4 and 5, and the lower edge 21 of said arm 18 is sharpened for co-action with the edge 14. In the angle between the major portion of this arm 18 and its downturned end 20, is a stop 22 adapted to strike the member 13 to limit the downward movement of the shank 17 and parts carried thereby.

A rod 23 is shown connected with the lower end of the shank 17 and with a foot lever 24, the latter being positioned between the legs 9 and fulcrumed at 25 to the bar or leg 7. A suitable spring 26 normally raises this foot lever and consequently 35 raises the shank 17 and parts carried thereby to the position of Fig. 1. By depressing the foot lever 24, however, said shank and parts are downwardly moved.

When the device is to be used for spreading a hook H of a worn or broken cross chain C, the hook is engaged with the chisel-like members 13 and 20, in the manner shown in Fig. 2 and then the foot lever 24 is depressed, causing said members to effectively open the hook as shown in Fig. 3, so that it may readily be disconnected from the side chain. When the device is to be used for closing the hook of a cross chain, after application thereof to a side chain, the sharpened edges 14 and 21 come into play, as will be clear from Figs. 4 and 5. The hook is engaged with the edge 14 in the manner shown in Fig. 4 or in a reversed position and when lever 24 is depressed, the edge 21 100 of the arm 18 moves toward said edge 14 thus closing the hook.

It will be seen from the foregoing that the invention is simple and inexpensive, may be easily manufactured and sold at 110 small cost, and will be efficient and rapid in operation. On account of such advantages

as these, the details disclosed are preferably followed. However, within the scope of the invention as claimed, variations may of course be made.

5 I claim:—

1. A chain tool comprising a standard having its upper end formed by a rigid upwardly extending bar, said bar having a chisel-like member at its upper end, a shank slidably engaging an edge of said bar and having a yoke slidably surrounding the latter, an arm projecting laterally from the upper end of said shank, said arm having a downturned chisel-like member co-operable with the first named member to open the hook of a cross chain, and means for downwardly pulling said shank.

2. A chain tool comprising a standard having its upper end formed by a rigid upwardly extending bar, said bar having a chisel-like member at its upper end, a shank slidably engaging an edge of said bar and having a yoke slidably surrounding the latter, an arm projecting laterally from the upper end of said shank and having a downturned chisel-like member co-operable with the first named member to open the hook of a cross chain, co-operable means on said bar and the arm of said shank to close the hook of a cross chain, and means for downwardly pulling said shank.

3. A chain tool comprising a standard

having its upper end formed by a rigid upwardly extending bar, said bar having a sharpened upper edge and an upstanding chisel-like nose, a shank slidably engaging an edge of said bar and having a yoke slidably surrounding the latter, an arm projecting laterally from the upper end of said shank, said arm having a sharpened lower edge co-operable with the sharpened upper edge of said upwardly extending bar and having a down turned chisel-like member co-operable with said upstanding nose and means for downwardly pulling said shank. 45

4. A chain tool comprising two vertically disposed parallel bars having their lower ends directed outwardly to form supporting legs, a third leg secured between the intermediate portions of said bars, a relatively short bar secured between the upper ends of said first named bars, a shank having a yoke slidably surrounding said short bar, said shank having a laterally projecting member co-operable with the upper end of said short bar to effect bending of a cross chain hook, a foot lever between the first named legs and pivoted to the third leg, and an operating connection between said foot lever and said shank for downwardly moving the latter. 60

In testimony whereof I have hereunto affixed my signature.

JESSE CHENOWETH.
